CONTROL MEANS FOR WRINGER DRIVE MECHANISM

Peter Eduard Geldhof, Syracuse, N. Y., assignor to Easy Washing Machine Corporation, Syracuse, N. Y., a corporation of Delaware

Application August 13, 1934, Serial No. 739,528

18 Claims.

(Cl. 68—32)

This invention relates to improvements in the drive mechanism for a clothes wringer of the pressure roll type.

The main object of the invention is to provide a power-operated pressure roll wringer for clothes washing machines or the like with means whereby when the pressure on the wringer rolls is released, the drive for the rolls will be automatically discontinued so that the rolls will cease to rotate.

In carrying out the above-mentioned object, I have provided a pressure roll wringer with the conventional drive mechanism comprising a drive shaft adapted to be rotated by a source of power such as an electric motor or the like; two drive pinions arranged in opposed relation and which are in constant mesh with a driven gear operably connected with one of the wringer rolls, and a reversing gear or clutch member driven by the drive shaft and manually movable from a neutral position into engagement with the pinions for determining the direction of rotation of the rolls.

To this conventional drive mechanism I have added a novel control means operably connected to the reversing gear or clutch member and to the pressure applying mechanism for the wringer rolls in such a manner that when the pressure on the rolls is released by the manipulation of a safety release member the control device will automatically return the reversing gear or clutch member to the neutral position and thereby disconnect the rolls from the power drive means.

A more specific object of the invention resides in providing a control mechanism of the above-mentioned class which will function by its own inherent power independently of the power-operated drive means for the rolls of the wringer to automatically operate the reversing clutch member of the roll drive mechanism.

Another object is to provide the power drive mechanism of a pressure roll wringer with a control device that will be automatically moved to a predetermined cocked position ready to function when the pressure-applying mechanism and reversing member are moved to their respective effective positions.

A further object of the invention is to provide a control means for the conventional drive mechanism of a pressure roll wringer which is simple, compact and economical in construction and which may be readily incorporated therein.

Other objects and advantages pertaining to the details of the structure and to the form and relation of the parts thereof will more fully appear from the following description taken in connec-

tion with the accompanying drawings in which:—

Figure 1 is a side elevation of a roll wringer embodying the various features of this invention, together with a portion of the upper end of a washing machine vat with parts thereof broken away and shown in section.

Figure 2 is an enlarged detail vertical sectional view taken substantially on line 2—2, Figure 3, looking in the direction indicated by the arrow.

Figure 3 is an enlarged horizontal sectional view of the gear case and the adjacent end of the wringer together with a portion of the upper end thereof with my novel control device associated therewith.

Figure 4 is a detail horizontal sectional view taken substantially in the plane of the line 4—4 Figure 3, illustrating the trigger mechanism for maintaining the control plate in the latched or cocked position and a portion of the means actuated by the safety device of the wringer for operating the trigger mechanism.

Figure 5 is an inner face view of the transmission cover taken substantially in the plane of the line 5—5, Figure 3, and illustrating the spring actuated control plate and the trigger mechanism associated therewith in elevation.

Figure 6 is a detail transverse vertical sectional view through the trigger mechanism and adjacent portion of the control plate taken on line 6—6 Figure 5.

Figure 7 is a perspective view of the trigger mechanism for holding the control plate in the latched or cocked position.

The instant application relates to the same subject matter of invention embodied in my co-pending applications Serial No. 694,428 filed October 20, 1933 and Serial No. 699,937 filed November 27, 1933, and Serial No. 699,938 filed November 27, 1933. These co-pending applications differ from the present application and from each other mainly in the operation and construction of the control means for the power means for operating the wringer rolls. For instance, in application Serial No. 694,428, the driving clutch element is provided with a plurality of cam surfaces cooperating with a plurality of push buttons whereby the power of the drive shaft is utilized to engage or disengage the drive clutch element either upon manual operation of the push buttons or upon release of the safety device.

Application Serial No. 699,937 comprises a clutch means connected directly with the drive shaft for operating the wringer rolls. This clutch means is associated with a push rod and with the safety device for the wringer rolls whereby the

power of the drive shaft may be utilized for engaging or disengaging the conventional drive clutch element either upon manual operation of the push rod or upon release of the safety device.

5 Application Serial No. 699,938 embodies a pair of planetary gear systems and control means therefor whereby the wringer rolls may be operatively connected or disconnected with the drive shaft by a manually operated means or by the 10 release of the safety device for the wringer rolls. In the present application, there is provided a control mechanism which functions independently of the power drive means for the wringer rolls and which is so connected with said power drive 15 means and with the safety device for releasing the spring pressure of the wringer rolls that the drive mechanism will be automatically disconnected thereby by the release of the safety device.

20 The device as illustrated in the drawings comprises a pressure roll wringer indicated at 1 secured at one end to a transmission case 2 of the power drive mechanism for the wringer rolls. The transmission case 2 contains substantially 25 all of the mechanism comprising this invention and is mounted upon the upper end of a tubular drive shaft housing 3 adapted to contain the usual drive shaft 4.

20 The housing 3 may be secured in any well known manner to the side of a washing vat A while the shaft 4 may be operably connected to a suitable power unit such as an electric motor or the like with which a washing machine is provided in the usual manner.

35 The transmission case 2 is rotatively mounted upon the housing 3 so that the wringer 1 may be swung in a horizontal plane about the axis of the housing from a position over the washer vat to one or more positions at one side of said vat 40 and then be releasably secured in any one of these positions in a manner presently described, and inasmuch as these members do not constitute any part of this invention, it is thought that further illustration or description thereof is unnecessary.

45 The wringer 1 is constructed in the conventional manner and comprises a pair of rollers 6 and 7 mounted one upon the other in a frame composed, in this instance, of two vertically disposed end members 8 and 9 substantially U-shaped in cross section and which are tied together at their lower ends by a suitable cross member 10. An upper cross member or head 11 of substantially U-shaped formation is mounted upon the upper ends of the side members 8 and 9 and is detachably connected at one end with one of the side members as 9 by a catch arrangement indicated at 12 formed by pressing adjacent portions of the head and side member outwardly. The other end of the head 11 is pivotally connected by a bolt 60 13 to the upper end of a U-shaped lock bar 14 positioned in the end member 8 and which is designed to releasably secure the head 11 in place in a manner hereinafter more fully explained.

55 The rolls 6 and 7 are mounted in suitable bearings provided in the frame sides 8 and 9. The lower roll as 7 may, as shown in Figure 3, be mounted in a swinging U-shaped bracket 16 which is supported on a transverse rod 17 mounted in the frame end 8 above the roll shaft 18. The upper roll 6 is guided in the wringer frame by bearing members 20 which engage the upper surface of the shaft 21 of the roll. The upper roll is yieldingly pressed into engagement with the lower roll 7 with greater or less pressure 70 determined by a pressure spring 23 extending lon-

gitudinally through the head 11 with the ends thereof resting upon the upper face of the upper roll bearings 20. The tension of the spring 23 may be manually controlled in any suitable manner as by a tension screw 24, mounted in the head 11 intermediate the ends thereof in the conventional manner.

5 The wringer 1 is secured to the case 2 by a pair of screws 25 which pass through registering holes formed in the side wall of the case 2 and a pair 10 of outwardly bent flanges 26 formed on the frame end 8. The transmission case 2 is a substantially rectangular box-like member formed with the end thereof opposite the wringer 1 open.

A cover member 28 is secured to the case 2 15 for closing said open side by any suitable means such as the screws 29. The case 2 has a pendant boss 30 provided with a shaft opening 31 which rotatably receives the upper end portion of the tubular housing 3. The upper end of the housing 3 engages the inner end wall 31' of the opening 31 for limiting the downward movement of the case 2 on the housing 3.

20 It will now be understood that the case 2 and wringer 1 may be readily swung in a horizontal 25 plane about the housing 3 as a pivot to a plurality of predetermined positions as from a position over the washing vat to required positions at one side of said vat over a laundry tray or the like, not shown. The case and wringer may be releasably 30 secured in adjusted position by any suitable means, as the spring-actuated lock pin 33 mounted in the boss 30, for engagement with a selected one of a plurality of circumferentially spaced holes 34 provided in the upper end portion 35 of the housing 3.

25 The upper end of the drive shaft 4 terminates, in this instance, a short distance below the upper end of the housing 3 and has a pin and slot connection as indicated at 35 with the lower end of 40 a vertically disposed stub shaft 36 which extends upwardly into the case 2, as shown in Figure 3, so that the case and wringer may be readily removed from the housing 3 by a vertical movement thereof after the lock pin 33 has been withdrawn 45 from holding engagement with the housing 3.

30 The stub shaft 36 is journaled at its upper end in a pendant hollow boss 37 formed integral with the upper wall of the case 2 in co-axial alignment with the shaft opening 31. The shaft 36 is also 50 journaled intermediate its ends in a bearing member 38 formed in the lower wall of the case 2 at the upper end of the opening 31.

35 Rotatably mounted upon the shaft 36 is a pair of opposed bevel pinions 40 arranged in longitudinally spaced relation and which are in constant mesh with a bevel gear 41 journaled in the case 2 in the manner illustrated in Figure 3 of the drawings. That is, the gear 41 is provided with an outwardly extending hollow boss 42 which, in turn, is journaled in a hollow boss 43 formed on a vertical wall or partition 44 provided in the case 2.

40 The gear 41 is operably connected with the lower roll 7 for driving the same by means of 65 a flexible drive coupling 45 positioned in the gear hub 42 and which has a pin and slot connection as at 46 and 47 with the roll shaft 18 and gear 41 respectively.

45 Each of the pinions 40 is provided on the inner 70 face thereof with the usual inwardly extending clutch elements or teeth 40' adapted to be engaged by similar clutch elements or teeth 50' provided on opposite ends of a clutch member 50 which is slidably mounted on the shaft 36 inter- 75

mediate the pinions 40 for the purpose of transmitting motion from the shaft to said pinions, said clutch member 50 being keyed to the shaft 36 as at 51 so that the clutch member will be 5 positively driven by the shaft.

The clutch member 50 is provided with a peripheral annular groove 52 in which is positioned a roller 53 mounted on a stud 53' secured to a crank arm 54. The crank arm 54 is mounted 10 eccentrically on the square end of a shaft 55, which is journaled in the cover 28 in a horizontal plane substantially midway between the pinions 40 with the axis of said shaft extending substantially normal to and intersecting the axis of the 15 shaft 36. The shaft 55 extends through the cover 28 and has secured to the outer end thereof a suitable lever 56 adapted to provide a convenient handle by which the shaft 55 and crank arm 54 may be rotated.

20 In order that the clutch member 50 may be releasably maintained in the neutral position substantially midway between the pinions 40, I have provided a friction member for engaging the shaft 55 adapted to releasably maintain said shaft 25 against rotation and which comprises in this instance a spring-pressed ball or pin 58 mounted in the cover 28 and which is adapted to engage in a recess 59 formed in the adjacent portion of the shaft 55 and which registers with said member 58 when the roller stud 53' is co-incidental with the horizontal plane passing through the axis of the shaft 55.

It will now be observed that the mechanism thus far described is constructed and operates in the conventional manner to rotate the wringer rolls 6 and 7. That is, the clutch member 50 is positively driven by the shaft 36 which, in turn, is rotated by the constantly rotating drive shaft 4; the wringer rolls may be rotated in one direction or the other as desired by swinging the handle 56 from the upright position as shown in Figures 1 and 3 to bring the clutch into operative engagement with one or the other of the pinions 40, depending upon the desired direction of rotation of the rolls and the driving action of the shaft upon the rolls 6 and 7 may be manually discontinued by simply returning the handle 56 to the normal or vertical position and thereby return the clutch member 50 to the neutral position out of engagement with the pinions 40 substantially midway therebetween.

In order that the clutch member 50, when in driving engagement with either one of the pinions 40, may be automatically returned to the 55 neutral position out of driving engagement with said pinions when the pressure on the rolls 6 and 7 is released, I have provided the power transmission mechanism for the rolls with a novel control mechanism associated with the 60 clutch member operating shaft 55 and with the wringer head lock bar 14. This control device comprises, in this instance, a slide member or plate 60 mounted in the cover 28 and which is guided for vertical reciprocatory movement in suitable guideways or grooves 61 and 62 formed in the inner face of corresponding inwardly projecting bosses or flanges 63 and 64 secured to or made integral with the cover 28 adjacent respectively the upper and lower ends thereof, as shown 65 more clearly in Figure 5.

The plate 60 is provided with a longitudinally extending slot 65 near the upper end thereof adapted to receive the shaft 55 therethrough so as 70 to permit the free rotary movement of the shaft

and at the same time provides for the required longitudinal sliding movement of the plate 60 in the grooves 61 and 62. The plate 60, in this instance, is positioned in a vertical plane intermediate the crank arm 54 and the side wall of the cover 28 and is maintained in sliding engagement with the grooves 61 and 62 by the shaft 55 which is enlarged in diameter to extend beyond the sides of the slot 65 over the adjacent surface of the plate 60 as illustrated at 66, Figure 3.

The upper end of the slide 60 is connected with the crank arm 54 by means of a connecting link 67 which has one end thereof pivotally secured by a pin or stud 68 to the crank arm 54 eccentric to the shaft 55 and at substantially right angles to the stud roller 53. The other or upper end of the link 67 is secured to the plate 60 by a shouldered stud 69 secured to said plate and which passes through an elongated slot 70 provided in the link 67, said slot being of sufficient length to permit the free rotary movement of the shaft 55 and crank arm 54 necessary to manipulate the clutch member 50 when the plate 60 is in its lowermost inoperative or cocked position.

The plate 60 is normally urged upwardly by a pair of tension springs 72 positioned one adjacent either side of the major portion of the plate 60 with the upper ends thereof secured to the cover 28 by respective studs 73, while the other or lower end of each spring is secured to a respective side 30 of the plate 60 as at 74. The plate 60 is releasably held in its lowermost inoperative position against the action of the springs 72 by a trigger mechanism 75.

This trigger mechanism comprises a latch 35 member 76 mounted on the cover 28 adjacent the inner face of the plate 60 at the lower end thereof, and a trigger rod 77 which operatively connects the latch member with the lock bar 14 of the wringer 1. The latch member 76, in this instance, comprises a substantially U-shaped frame 78 which has the ends thereof pivotally connected by a pair of pins 79 to a supporting bracket 80 secured by screws 81 or other suitable means to the lower end wall of the cover 28. The pins 45 79, in this instance, are screw threaded or otherwise secured to the bracket 80 and extend into corresponding apertures 82 formed in the side members 78' of the frame 78.

The latch frame 78 has the transverse portion 50 78'' thereof provided with a lateral projection 83 which extends upwardly from substantially the central portion thereof for supporting a catch or 55 detent 84. The detent 84 is also a U-shaped member having the sides as 84' thereof pivotally connected as at 85 to the member 83 adjacent the upper ends thereof, while the outer edge of these side members are tapered or beveled outwardly from the upper ends thereof adjacent the pivot 85 to the lower end for extending beyond the projection 83 into a transverse elongated slot 86 provided in the lower end of the plate 60.

The side members 84' of the detent 84 are automatically urged outwardly toward the plate 60 by means of a coil spring 87 mounted on the pivot 65 shaft 85 intermediate the members 83' of the projection 83 with one end thereof engaging said projection and the other end engaging the transverse portion as 84'' of the detent 84. The outward swinging movement of the detent 84 produced by the action of the spring 87 is limited by the engagement of the transverse portion 84'' of the detent with the adjacent portion of the members 83' of the projection 83 as illustrated in Figures 4 and 5.

The frame 78 is also provided with a horizontally disposed rearwardly extending flange 89 positioned at one side of the projection 83 in the path of movement of the trigger rod 77 to be engaged by said rod for releasably preventing the inward pivotal movement of the latch frame about the pins 79 when the detent 84 is in holding engagement with the plate 60.

The trigger rod 77 extends inwardly in a substantially horizontal plane from the latch frame 78 through the transmission case 2 and is slidably mounted for longitudinal movement in bearing members 38' and 80 provided respectively on the bearing member 38 and partition 44. The trigger rod 77 is provided with a stop member 91 comprising in this instance a snap ring adapted to engage the outer end of the bearing member 38' for limiting the inward movement of said rod. The inner end of the rod 77 terminates in the wringer frame end 8 adjacent one side member 92 of the hereinbefore mentioned U-shaped lock bar 14 comprising a member of the safety pressure release mechanism incorporated with the wringer 1.

This safety pressure release mechanism, as illustrated in the drawings, is a well-known type of safety control for wringer rolls and as more fully described in my co-pending application, Serial Number 694,428, it comprises briefly the hereinbefore mentioned U-shaped lock bar 14 having, as before stated, the upper ends of the side arms 92 pivotally connected to the head 11 at 13 and extends downwardly from said pivot through the frame end 8 between the rod 77 and a similarly disposed rod 93 with the lower ends of the arms terminating near the bottom of the frame end and connected by a transverse portion 94.

Each arm 92 of the lock bar 14 has a longitudinal notch 95 in a vertical edge thereof for receiving the pin 17 therein and a cam surface 96 in the opposite edge adapted to engage the rod 93 as the lock bar 14 is being moved downwardly to the lowermost position.

The recesses 95, cam surfaces 96, and the rods 17 and 93 are so related that when the head 11 and lock bar 14 are moved downwardly toward the lowermost position, the lower end of the lock bar will be swung outwardly by the engagement of the cam surface 96 with the pin 93 toward the pin 17 so that when the head 11 and lock bar 14 are in the lowermost position, the lower end of the lock bar will be in the outermost position with the rod 17 registering in the slot 95 adjacent the lower end thereof, to prevent direct upward movement of said lock bar.

The lock bar 14 is releasably maintained in its lowermost position by a substantially horizontally disposed catch plate 98 pivotally mounted at its inner end as at 99 to the cross frame 10 in spaced relation to the lock bar 14. The other or free end of the catch plate extends beneath the transverse portion 94 of the lock bar and is yieldingly maintained in contact therewith by means of a compression spring 100 mounted on a guide rod 101 which is connected with the catch plate and cross member 10 for also limiting the upward movement of the catch plate.

The catch plate 98 is provided with upwardly extending flanges 102 adjacent each longitudinal edge thereof which are adapted when the plate is in its uppermost position in contact with the transverse portion 94 of the lock bar to abut the inner side of said transverse portion and prevent inward swinging movement of the lock bar.

The catch plate 98 is moved downwardly against

the action of the spring 100 by a trip plate 104 which is pivotally mounted at 105 to the wringer frame. This trip plate is disposed in nearly a vertical plane with the lower end thereof in engagement with the side flanges or abutment members 102 of the catch plate 98. The upper end of the trip plate 104 extends some distance above the pivot 105 and is in the path of movement of the lower end of a pair of rock arms 106, one of which is shown in Figure 3.

These rock arms are similar in construction and extend vertically through the frame end 8, one adjacent either side thereof, and are pivotally mounted intermediate their ends upon the hereinbefore mentioned rod 93. The arms 106, may, as shown, be connected by a cross member 107 whereby said arms will rock in unison.

The upper ends of the arms 106 terminate a short distance below the upper end of the frame end 8 and each is connected with a pin 109 which extends outwardly through an elongated slot 110 in the respective sides of the frame end 8. These pins 109 are each connected at their outer ends to one end of a corresponding safety release bar 111 in the conventional manner through the medium of a suitable link mechanism indicated at 112.

The safety release bars 111 are usually positioned one at either side of the wringer frame and have the ends thereof opposite the pins 109 connected through a suitable link mechanism, not shown, to the frame end member 9. The safety release bars are normally maintained in their outermost position in spaced relation to the wringer frame and the linkage connection between said bars and the frame end 9 and the rock arms 106 are such that when one or the other of the bars 111 are pressed inwardly toward the wringer frame, the pins 109 and, therefore, the upper ends of the rock arms 106 will be moved outwardly causing the arms to rock about the rod 93 as an axis. This outward movement of the upper ends of the arms 106 obviously produces a corresponding inward movement of the lower ends of the arms which will rock the trip plate 104 about the pivot 105 and thereby press the latch plate 98 downwardly sufficiently to bring the abutment members 102 out of holding engagement with the lock bar 14. As the catch plate 98 releases the lower end of the lock bar, said bar will then be caused to swing inwardly out of holding relation with the rod 17 due to the action of the pressure spring 23 which, it will be remembered, is connected with the wringer head 11 and tensioned to normally separate said head and the bearing members 20 so that as soon as the lock bar 14 moves out of holding engagement with the rod 17 the spring 23 will cause the lock bar and head 11 to quickly move upwardly and thereby release the tension of said spring upon the upper wringer roll 6.

It will therefore be obvious that, as soon as the lock bar 14 is released by the catch plate 98, and the lower end thereof is caused to swing inwardly by the action of the spring 23 as the lock bar is moved out of engagement with the rod 17, the trigger rod 77 will be released by the lock bar and be free to move inwardly from holding engagement with the latch frame 78. As soon as the latch frame 78 is thus released by the lock bar, the action of the springs 12 upon the plate 60 tending to draw said plate upwardly will cause the detent 84 to move out of holding engagement with the plate 60 by effecting the inward rocking movement of the latch frame 78 about the pivots 79.

sufficiently to carry the detent inwardly out of holding engagement with the plate.

This upward movement of the plate 60 will produce a corresponding movement of the connecting link 67 until said link assumes a straight vertical position as illustrated by full lines in Figure 5, whereupon further upward movement of the plate will be prevented by said link due to the connection thereof at the lower end with the crank arm 54 which will have been moved to a position where the stud 68 is in a vertical plane over the axis of the shaft 55.

Operation

Assuming that the wringer head 11 and lock bar 14 are in their lowermost positions for maintaining a constant pressure between the wringer rolls 6 and 7 through the medium of the spring 23 and that the control plate 60 is maintained in its lowermost cocked position against the action of the springs 72 by the trigger mechanism, as illustrated by full lines in Figures 3 and 5, it will now be obvious that the stud 69 will be in its lowermost position so that the link 67 is free to move downwardly until the upper end of the slot 70 engages the stud 69 and thereby permit sufficient free rocking movement of the crank arm 54 to bring the roller 53 from a position in the horizontal plane of the axis of the shaft 55 at one side thereof into a position in a vertical plane either above or below said shaft for the purpose of moving the clutch member 50 axially along the shaft 36 into clutching engagement with one or the other of the pinions 40.

It will now be readily understood that when the control plate 60 is in its lowermost inoperative position that the clutch member 50 may be moved in the conventional manner by the manipulation of the lever 56 from the neutral position intermediate the pinions 40 into clutching engagement with either one of the pinions 40 for operatively connecting the shaft 36 with the roller shaft 18 for producing a corresponding rotary movement of the rollers 6 and 7. Likewise, the clutch member 50 may be returned to the neutral position out of clutching engagement with the pinions 40 by manipulating the lever 56 in the conventional manner.

If, however, the clutch member 50 is in clutching engagement with one of the pinions 40, for instance, the upper positioned pinion as viewed in Figure 3, it will be obvious that the roller 53 will then be in the vertical position above the axis of the shaft 55 and that the stud 68 will be positioned at the right of the shaft 55 as viewed in Figure 3 in the horizontal plane of the axis of said shaft, as indicated by dotted lines in Figure 3, and the stud 69 will be positioned adjacent the upper end of the slot 70 in the link 67 due to the link being drawn to its lowermost position by the stud 68.

Assuming now that when the control plate 60 is in its lowermost position and the member 50 is in engagement with the upper pinion 40 so that one of the safety release bars 111 is pressed inwardly to effect the release of the pressure upon the rolls 6 and 7, it will follow that, as the trigger rod 77 is released from holding engagement with the latch frame 78 due to the inward movement of the lock bar 14 in the manner hereinbefore described, the control plate 60 will be released by the detent 84 and permitted to be moved upwardly by the action of the springs 72. The upward movement of the plate 60 will produce a corresponding movement of the connect-

ing link 67 through the medium of the stud 69 and thereby produce a rotary movement of the crank arm 54 and shaft 55 until the stud 68 and link 67 assume their uppermost positions in a vertical plane about the axis of the shaft 55.

This rotation of the shaft 55 and crank arm 54, will, of course, produce a corresponding rotation of the roller 53 which will return the clutch member 50 to its neutral position intermediate the pinions 40, thereby disconnecting the shaft 36 from the pinions and permitting the rollers 6 and 7 to cease rotating.

When the control plate 60 is in its uppermost operative position for yieldingly maintaining the clutch member 50 in the neutral position, this control plate may be readily brought to and secured in its lowermost cocked position without any specific action or conscious effort on the part of the operator in the following manner.

After the pressure on the wringer rolls has been released, it is obvious that before the wringer can again be utilized for drying clothes, fabric or the like, that the said pressure must be restored to the rolls which is accomplished in the usual manner by pressing downwardly on the head 11 until the lock bar 14 is secured in its innermost position by the engagement thereof with the rod 17 and catch plate 98. As the lock bar 14 is thus brought into its normal operative position, the trigger rod 77 will be automatically brought into engagement with the flange 89 of the latch member 76 and will rock said latch member about the pivot 79 into the operative position for holding the control plate 60 in its lowermost inoperative position, but inasmuch as the plate 60 is in its uppermost position, the holding portions 84' of the detent 84 will extend outwardly from the side of the latch frame 78 beneath the plate 60 in the path of movement thereof. The plate 60 may then be brought to its lowermost position without any conscious effort on the operator's part, by, and whenever the lever 56 is swung in either direction from the horizontal to bring the clutch member 50 into clutching engagement with one or the other of the pinions 40.

This movement of the plate 60 to the cocked position, as will be clearly understood by referring to Figure 3, is effected through the medium of the connecting link 67 and studs 68 and 69 in the following manner.

When the clutch member 50 is in a neutral position as before stated, the studs 68 and 69 will be in vertical alinement in the plane above the axis of the shaft 55 so that when the crank arm 54 and roller 53 is rotated to bring the clutch member 50 into engagement with one of the pinions 40, the stud 68 will likewise be rotated about the axis of the shaft 55 in a downward direction, thereby producing a corresponding downward movement of the plate 60 through the medium of link 67. As the plate 60 engages the upper portion of the detent-holding members or fingers 84', the detent will be rocked inwardly about the axis of the pivot 85 against the action of the spring 87 until the slot 86 registers with said finger portions of the detent, whereupon these finger portions will be moved into the slot by the action of the spring 87 in position to engage the plate at the lower side of the slot and thus again maintain the plate in its lowermost cocked position.

Although the control mechanism shown and specifically described herein is very simple in construction and operation, I do not wish to be

limited to the exact construction shown as various changes in the form and relation of parts thereof may readily be made without departing from the spirit of the invention as set forth in the appended claims.

What I claim is:

1. The combination with a safety device for releasing the spring pressure of a roll wringing mechanism, of manually controlled power drive means for rotating the wringer rolls in either direction, a power means independent of the power drive means and said pressure means adapted to disengage the power drive means to effect the stopping of rotation of the rolls, and means set into operation by the release of the safety device for effecting the operation of said power means.
2. A device as in claim 1, wherein the power means including a resilient member which is effective after the release of the safety device for maintaining the power drive means disengaged under yielding pressure.
3. The combination with a safety device for releasing the spring pressure of a roll wringing mechanism, of manually controlled means for driving the wringer rolls in either direction, a control device actuated by a source of power independent of said roll pressure and said drive means for moving said manually controlled drive means to a neutral position, and means set into operation by the release of the safety device for effecting the operation of said control means.
4. The combination with a safety device for releasing the spring pressure of a roll wringing mechanism, of a driving and reversing mechanism for the rolls, said mechanism including a drive clutch element, a pair of driven clutch elements, and manually operated control means for actuating the drive clutch element to bring the same into and out of engagement with the driven clutch elements to effect starting, stopping and reversing of the rolls, a control device actuated by a source of power independent of said roll pressure and said drive means for moving said drive clutch element to a neutral position, and means set into operation by the release of the safety device for effecting the operation of said control means.
5. The combination with a safety device for a roll wringing mechanism, of a drive mechanism for rotating the rolls, manually operated means for engaging and disengaging said mechanism, a control element operatively connected with the manually operated means for moving said means, retaining means associated with the control element and with the safety device for maintaining said control element in a position to enable the free operation of the manually operated means independently of the control element, means for releasing said retaining means upon operation of the safety device, and means operating independently of the drive mechanism for actuating the control element when said control element is released to disengage the drive mechanism.
6. The combination with a safety device for a roll wringing mechanism, of a drive mechanism for rotating the rolls, manually operated means for engaging and disengaging said mechanism, a control element movable from an inoperative to an operative position and operatively connected with the manually operated means whereby said manually operated means may be manually actuated independently of the control

element only when said control element is in the inoperative position, retaining means associated with the control element and with the safety device for maintaining said control element in the inoperative position and adapted to release said control element upon operation of the safety device, and resilient means for actuating the control element, when said control element is released to disengage the drive mechanism.

7. The combination with a safety device for releasing the spring pressure of a roll wringing mechanism, of a drive mechanism for rotating the rolls, manually operated means for engaging and disengaging said mechanism, a spring actuated control element movable to an inoperative position for tensioning the spring, means operatively connecting the control element with the manually operated means whereby said manually operated means may be operated independently of the control element only when said control element is in the inoperative position, retaining means associated with the control element and with the safety device for maintaining said control element in the inoperative position against the action of said spring and adapted to release said control element upon operation of the safety device whereby the control element will automatically disengage the drive mechanism when the pressure on the rolls is released by said operation of the safety device.

8. The combination with a pressure safety device for a roll wringing mechanism, of a drive mechanism for the rolls comprising a drive shaft and a clutch mechanism on the drive shaft, a casing for enclosing the clutch mechanism, manually operated means mounted in the casing and extending to the outside thereof for engaging and disengaging the clutch mechanism, separate control means disposed within the casing, and means including a spring for operating said separate control means independently of the drive shaft for automatically operating the clutch to discontinue the rotation of the rolls upon the release of the safety device.

9. The combination with a pressure safety device for a roll wringing mechanism, of driving mechanism including a clutch for rotating the wringer rolls, a casing for enclosing the driving mechanism, manually operated means mounted in the casing and extending to the outside thereof whereby the clutch may be manually operated to control the movement of the wringer rolls, a separate control element disposed in the casing, means operably connecting the control element with the clutch whereby said clutch may be operated by said manually operated means independently of the control element only when said control element is in an inoperative position, holding means for releasably maintaining the control element in the inoperative position, means controlled by the safety device for releasing said holding means when said safety device is operated, and means operating independently of the driving mechanism for automatically operating the control element to disconnect the clutch when said holding means are released.

10. The combination with a roll wringing mechanism having a safety device for releasably maintaining the rolls in pressure engagement, of driving mechanism for rotating the rolls, manually operated means for engaging and disengaging said mechanism to control the operation of said rolls, a control slide, trigger means for releasably maintaining the slide in a cocked position, means

operatively connecting the slide with the manually operated means whereby said manually operated means may operate independently of the control slide when said slide is in the operative position 5 and the mechanism will be disengaged automatically by the action of the slide when said slide is released, means for releasing said trigger means upon release of said safety device, and means for actuating the control slide when said slide is released by the trigger means.

11. The combination with a roll wringing mechanism having a safety device for releasably maintaining the rolls in pressure engagement, of driving mechanism for rotating the rolls, manually operated means for engaging and disengaging said mechanism to control the operation of the wringer, a spring actuated control slide, trigger means for releasably maintaining the slide in a cocked position to permit the free operation of 15 said manually operated means, means for releasing said trigger means upon release of said safety device, means including a lost motion linkage operably connecting the slide with the driving mechanism whereby said mechanism will be disengaged automatically by the action of the slide 20 when said slide is released, and means for returning said slide against the action of the spring into engaging relation with said trigger means upon manipulation of the manually operated means to 25 30 re-engage the driving mechanism.

12. The combination with a safety device for releasing the squeezing pressure of a roll wringing mechanism, of a drive mechanism for rotating the rolls, manually operated means for engaging and disengaging said mechanism, a control element connected by a lost motion linkage with the manually operated means, releasable means for maintaining said control element in a position such as to enable free control of said driving mechanism 35 40 by said manually operated means, means actuated by the safety device for releasing said releasable means, and spring means for removing said control element to disengage the driving mechanism upon release of said releasable means.

13. The combination with a safety device for releasing the spring pressure of a roll wringing mechanism, of a driving mechanism for rotating the rolls, manually operated means for controlling the operation of said driving mechanism, and 50 means operated by the safety device for disconnecting the driving mechanism upon operation of the safety device, said latter means comprising a spring operated control member.

14. The combination with a safety device for releasing the spring pressure of a roll wringing mechanism, of a driving mechanism for rotating the rolls, manually operated means for controlling the operation of said driving mechanism, and means operated by the safety device for disconnecting the driving mechanism upon operation of the safety device, said latter means comprising a control member, latch means for maintaining said control member in an inoperative position, and spring means for moving said control member to driving mechanism disengaging position.

15. The combination with a safety device for releasing the spring pressure of a roll wringing

mechanism, of a driving mechanism for rotating the rolls, manually operated means for controlling the operation of said driving mechanism, a control element for the driving mechanism, means comprising a latch for maintaining said control element in a position such as to enable free control of the driving mechanism by said manually operated means, means inter-connecting said safety device and said latch element for enabling movement of the latch element from control element maintaining position upon actuation of the safety device, and spring means for moving said control element to disengage the driving mechanism upon movement of the latch element. 5 10 15

16. The combination with a pressure safety device for releasing the spring pressure of wringer rolls, of a unitary driving and reversing mechanism for said rolls, a casing for housing said unitary driving and reversing mechanism, a drive shaft extending into said casing, said roll wringing mechanism extending and being supported from the casing, manually operated means mounted in the casing and extending to the outside thereof for controlling the operation of said driving and reversing mechanism, separate resiliently operated control means disposed within the casing, and means extending into the casing actuated by the safety device upon release thereof and acting independently of the drive shaft to enable said separate control means to automatically disconnect said driving and reversing mechanism. 20 25 30

17. The combination with a safety device for releasing the spring pressure of a roll wringing mechanism, of a driving mechanism for rotating the rolls, manually operated means for controlling the operation of said driving mechanism, and means operated by the safety device for disconnecting the drive mechanism upon operation of the safety device, said latter means comprising a spring operated control member effective for 35 40 45 yieldingly maintaining the drive mechanism disconnected when said spring pressure for the rolls is released by the safety device.

18. The combination with a safety device for releasing the squeezing pressure for a roll wringer mechanism, of a power drive means for rotating the wringer rolls in either direction, said drive means including a manually operated control member movable from and to a neutral position for effecting engagement and disengagement of the power means, a power operated means including a control element operatively connected with the control member whereby said movement of the member from the neutral position will move the control element to a cocked position and permit free operation of the control member independently of the control element when said element is in the cocked position, trigger means for releasably maintaining the control element in the cocked position, and trigger actuating means set into operation by the release of the safety device for releasing the control element whereby said power operated means may effect return of the control member to the neutral position for automatically stopping operation of the rolls. 50 55 60 65

PETER EDUARD GELDHOF.
